UNITED STATES PATENT OFFICE.

F

EDWARD S. RAFF, OF CANTON, OHIO.

INKSTAND.

SPECIFICATION forming part of Letters Patent No. 430,194, dated June 17, 1890.

Application filed February 10, 1890. Serial No. 339,949. (No model.)

To all whom it may concern:

Be it known that I, EDWARD S. RAFF, a citizen of the United States, and a resident of Canton, county of Stark, State of Ohio, have 5 invented a new and useful Improvement in Inkstands, of which the following is a full, clear, and exact description, reference being had to the accompanying drawings, making part of this specification.

10 My invention relates to improvements in an article of manufacture; and it consists in providing in an inkstand a fountain or receptacle to hold ink that may be so balanced or poised as to yield or swing when the pen is placed in the stand, which movement will cause a supply of ink to flow from the body or the fountain to the pen, and back into the fountain when the pen is removed, by which a supply of fresh ink is always provided for 15 the pen, and the whole body of ink in the fountain moved each time the pen is inked, by which movement the ink is prevented from settling, and as a result of such frequent movement is always in order for use.

20 With these ends in view my invention consists of certain features of construction and combinations of parts, as will be hereinafter described, and pointed out in the claims.

Figure 1 of the accompanying drawings is 25 a side elevation, partly in section, of an inkstand illustrating my invention. Fig. 2 is a plan view, and Fig. 3 is a perspective, of a fragment of the ink-fountain.

A is a base, which may be made of any 30 suitable material, having side frames B and B', at the top portion of which is provided a threaded perforation C, in which is turned a threaded stud D, the inner end of which is coned to correspond with a conical depression 35 E. (Shown in Figs. 2 and 3.)

40 At the upper portion of side piece B there is provided an oblong aperture F, in which is placed a slide G, having at its end portions a flange H, having a threaded perforation 45 adapted to receive the threaded portion of the thumb-screw J, by which the slide G may be moved back and forth in the aperture F. In said slide there is provided a curved slot K, hereinafter explained.

50 A fountain or ink-holder L, preferably made of glass, is provided, having a hollow body portion a, a neck portion b, projected out-

wardly, and about the upper end portion of which is provided an annular screw-thread c, and on the top portion of the body L is provided a flanged aperture d, said flange having an annular screw-thread e, to which is fitted a metal cap f, having a similar screw.

55 A mouth-piece M, made, preferably, of hard rubber and of the form shown in the drawings, is provided, said piece having upwardly-projected walls h, a downwardly-projected neck portion m, having a screw-thread K similar and adapted to the thread c on the neck of the fountain, and a central and downward projected tube portion n, the aperture of which is small, as shown.

60 On each side of the fountain L and diametrically opposite are provided conical depressions E, adapted to receive the ends of the 70 studs D, and on one side thereof is provided an outwardly-projected stud s, as shown in Fig. 3.

The ink-fountain, as described, is placed in the supporting stand or frame composed of the 75 base A and side frames B and B', the inner ends of the stud D placed in the depressions E, and the stud s in the curved slot K.

In operation a sufficient amount of ink is 80 passed through the aperture provided therefor into the fountain to immerse or cover the end of the tube n to a point indicated by the dotted line, the swing or tip of the fountain to be regulated or gaged by the slide G, which may be moved back or forward and adjusted 85 to the amount of ink in the fountain, so as to prevent an excess rising through the tube n, and by keeping the end of the said tube constantly immersed air bubbles rising above the tube into the mouth M will be prevented, and 90 by the frequent swinging movement of the fountain the ink is not liable to "settle," as is the case with a stationary fountain or one that is not so moved at every inking of the pen. To ink the pen, it is placed in the mouth M, 95 and by a gentle downward pressure the fountain will swing on its pivotal connection with the supporting-frame, the neck and mouth down and the rear portion of the body up, until such movement is arrested by the stud s 100 coming in contact with the rear end of the slot K. When a desired amount of ink has flowed from the fountain up through the tube n into the mouth and when the pen has been

inked and removed, the fountain will swing back into its normal position, as shown in Fig. 1. By the use of the thumb-screw J the tip of the fountain may be regulated by moving 5 the slide G back or forward to meet the stud s sooner or later in the course of the swing of the fountain.

Having thus fully described the nature and object of my invention, what I claim as new, 10 and desire to secure by Letters Patent, is—

1. As an article of manufacture, an inkstand having a support consisting of a base A and side frames B B', said frames having at their apex pivots D, and side frame B having at its 15 upper portion a slot F and slide G, adapted to be moved back and forth therein by the thumb-screw J, and an ink-fountain L, pivotally secured in said frame, to be tipped or swung on said pivots and to be adjusted by

the thumb-screw and slide, substantially as 20 described.

2. In an inkstand, the supporting-frame described and an ink-fountain pivotally secured therein, said fountain having a body portion L, depressions E, diametrically opposite, a 25 stud, as s, to engage an adjustable portion of said frame, a neck portion b, surmounted by a hard-rubber mouth-piece having a central tube portion n, and means for adjusting the swing of said fountain in said frame, substantially as described, and for the purpose 30 set forth.

In testimony whereof I have hereunto set my hand this 3d day of February, A. D. 1890.

EDWARD S. RAFF.
